UNITED STATES PATENT OFFICE.

ROBERT C. MATHES, OF NEW YORK, N. Y., AND HARRY S. READ, OF EAST ORANGE, NEW JERSEY, ASSIGNORS TO WESTERN ELECTRIC COMPANY, INCORPORATED, OF NEW YORK, N. Y., A CORPORATION OF NEW YORK.

VACUUM-TUBE CIRCUITS AND METHOD OF OPERATING THEM.

1,426,755.

Specification of Letters Patent. Patented Aug. 22, 1922.

Application filed May 9, 1919. Serial No. 295,820.

To all whom it may concern:

Be it known that we, ROBERT C. MATHES, and HARRY S. READ, citizens of the United States, residing at New York, in the county of Bronx and State of New York, and at East Orange, in the county of Essex and State of New Jersey, respectively, have invented certain new and useful Improvements in Vacuum-Tube Circuits and Methods of Operating Them, of which the following is a full, clear, concise, and exact description.

This invention relates to vacuum tube circuits, and more particularly to multistage amplifier circuits in which vacuum tubes are employed in the various stages.

It is well known in the art that a vacuum tube of the three electrode type, for example, will reproduce in amplified form in its output circuit impulses impressed upon its input terminals, and that the amplified impulses may be impressed on the input terminals of other tubes to give any desired degree of amplification. When such a multistage amplifier is employed to amplify low frequency impulses, it is generally preferable to have a direct coupling instead of an inductive coupling between stages in order that the low frequency impulses will be accurately reproduced by the amplifiers. But when such a direct coupling is employed considerable difficulty is experienced when signals are being received from preventing the output current of one tube from so affecting the potential applied to the control electrode of a second tube that the second tube is either blocked or has its amplifying action destroyed on account of its control electrode becoming too positive or too negative. In accordance with this invention, it has been found that the operation of such a multistage amplifier set is considerably improved by providing adjustable sources of potential for the control electrodes of the tubes, and by providing switching means between the stages whereby the output current of each tube may be given its proper value by adjusting the normal source of potential for its control electrode independently of this influence of the output current of the preceding tube. This invention will be more fully understood by reference to the following detailed description taken in connection with the accompanying draw-

ing which shows one embodiment of this invention in connection with a three stage amplifier set.

Referring to the drawing, 3, 4 and 5 are vacuum tube amplifiers having filaments 6, 7 and 8, anodes 9, 10 and 11 and control electrodes 12, 13 and 14 respectively. Each of these filaments may have a resistance of the order of 4 ohms. 16 is a source of heating current for the filaments, and it is to be noted that starting with the positive pole 65 of the battery 16, the heating current goes through the filament 8, 6 and 7 in the order named. Output circuit current for tube 3 is supplied from battery 18, while the output circuits of tubes 4 and 5 are supplied 70 from battery 19. A source of potential for the grid 12 is secured by the IR drop in that part of resistance 20 which is included in circuit between the grid and the filament 6. An adjustable contact 21 is provided 75 for varying the amount of the potential applied to the grid. This resistance 20 which in one case had a value of 170 ohms, is in the heating circuit for the filaments and is in shunt to filament 7 and a small resistance 80 22, the function of which will be described later.

The input circuit for tube 3 may be traced through high resistance 23, contact 21, a portion of resistance 20 to filament 6. The 85 output circuit for tube 3 may be traced from the anode 9, jack 25, high resistance 26, a source of voltage 18 and either through resistance 20 or resistance 22 and filament 7 to filament 6.

The input circuit for tube 4 includes switch 27, contact 28, source of voltage 29, jack 25, resistance 26 and through source of voltage 18 to the cathode 7. Since the two sources of voltage 18 and 29 are poled oppositely, the 95 potential of grid 13 depends upon the potential of these two sources and the value of the IR drop in resistance 26 and may be regulated by means of contact 30. Resistance 22 will generally be of such a small value that the 100 IR drop in it due to battery 18 may be neglected in this instance. When switch 27 is moved to contact 32 the input circuit of tube 4 is disconnected from the output circuit of tube 3 and contains only the small resistance 22. Therefore with the switch 27 on contact 32 the potential of the grid 13 is determined effectively by the IR drop in

resistance 22, the effect of the high shunt resistance 20 being negligible in this case. The output circuit for tube 4 may be traced from anode 10, jack 35, resistance 36, source 5 of voltage 19 to the cathode 7.

The input circuit for tube 5 includes source of voltage 37, switch 38, contact 39, jack 35, resistance 36, source of voltage 19 and the filament heating circuit to cathode

- 10 8, so that the potential of the grid 14 would depend upon the resultant potential of the oppositely poled sources 19 and 37 and the drop in potential in resistance 36; the resultant potential of grid 14 may be regulated by means of adjustable contact 40. However, when switch 38 is moved to contact 41 the input circuit for tube 5 is disconnected from the output circuit of tube 4 and contains only the source of voltage 37.
- 20 The output circuit for tube 5 includes the jack 42, a receiving device such as an oscillograph 43, battery 19 and the filament heating circuit to filament 8.

The manner in which such an amplifier 25 set may be adjusted for proper working may be explained as follows. A measuring instrument should be connected in the output circuit of tube 3 by means of jack 25, and the value of the output current ad- 30 justed to its best working value by varying the potential of the grid 12 through adjustment of contact 21. Preceding this operation switch 27 should be moved to contact 32, in order to prevent battery 18 from 35 supplying current to the input circuit of tube 4. If the battery 18 were allowed to supply current to tube 4, the adjustment of tube 3 might be appreciably affected thereby.

40 In order to adjust tube 4 for best working operation, switch 27 should be kept on contact 32, thereby disconnecting tube 3 from the input circuit of tube 4, and switch 38 should be moved to contact 41 in order 45 to prevent battery 19 from supplying current to the input circuit of tube 5. The potential of grid 13 is determined effectively by the IR drop in resistance 22, which should be of such a value as to give the 50 proper space current between the cathode and anode of tube 4, and of such a value as would maintain the grid always negative when normal signalling currents are passing through the amplifier. In one case, resistance 22 had a value of one ohm. The measuring instrument should be inserted in the output circuit of tube 4 by means of the jack 35 and the value of the current noted. Switch 27 should then be 55 moved to contact 28 and the value of the source of voltage 29 adjusted until the space current for tube 4 has the same value it had with switch 27 on contact 32. In order to 60 get this adjustment accurately, it may be necessary to adjust slightly contact 21 on

resistance 20, which will not change appreciably the output current of tube 3, but will produce appreciable changes in the output current of tube 4 due to the amplifying power of the tube. After these adjustments the potential relation of grid 13 to filament 7 is the same as was initially determined by the IR drop in resistance 22.

In a similar manner switch 38 should be moved to contact 41 and the value of 75 source of voltage 37 adjusted to give the normal grid potential to tube 5. For example, if tube 4 in normal operation produces a maximum change in the potential of grid 14 of 20 volts, battery 37 should be 80 adjusted to a value slightly greater, say 22 volts, in order to maintain grid 14 always negative. The value of the space current of tube 5 for this setting should be noted by the instrument connected in the output 85 circuit through jack 42. The switch 38 should then be moved to contact 39 and the effective value of battery 37 adjusted until the space current has the same value it had with switch 38 on contact 41. The set is 90 then ready to be employed as the amplifier for signals impressed across the terminals of resistance 23.

It is obvious that various changes may be made in the circuit arrangement above 95 described without departing in any wise from the spirit of this invention as defined in the appended claims.

What is claimed is:

1. A plurality of vacuum tubes each having an input circuit and an output circuit, the output circuit of one of said tubes being associated with the input circuit of a second of said tubes, each of said tubes comprising a cathode and a control electrode, 100 means for supplying current to said cathodes, and means for supplying a difference of potential between the cathode and a control electrode of one of said tubes, said means comprising the potential drop in a 105 resistance connected in shunt to a cathode of a succeeding tube.

2. A plurality of vacuum tubes each having a cathode, an input circuit and an output circuit, the output circuit of one tube 115 being associated with the input circuit of another of said tubes, and a resistance in shunt to one of said cathodes, said resistance being included in the input circuit of a tube preceding the tube having the shunted cathode. 120

3. A plurality of vacuum tubes each having a cathode, an input circuit and an output circuit, the output circuit of one vacuum being associated with the input circuit of 125 another of said vacuum tubes, the input circuit of one of said tubes including the cathode of a succeeding tube.

4. A plurality of vacuum tubes each having a cathode, a control electrode, an in- 130

put circuit and an output circuit, the output circuit of one of said tubes being associated with the input circuit of another of said tubes, means for supplying current to 5 said cathodes, and means for applying potential to one of said control electrodes comprising the drop in potential across the terminals of a cathode of a succeeding tube.

5. The combination of a plurality of 10 vacuum tubes connected in tandem, each of said vacuum tubes having an input circuit and a filamentary electrode, the input circuit of one of said tubes including said electrode of a succeeding tube.

15. 6. The combination with a vacuum tube having a control electrode and a filament, of a source of current for heating said filament, a resistance traversed by current from 20 said source, a source of voltage for said control electrode, switching means for connecting at times said control electrode with said source of voltage, and at other times for connecting said electrode to that terminal of said resistance which is electrically 25 remote from said filament.

, 7. The method of operating a plurality 30 of vacuum tubes in which the output current of one of said tubes controls the input potential applied to a second tube, said first and said second tubes each having a control electrode and a cathode, which method comprises controlling the potential of the control electrode of said first tube in accordance 35 with the potential difference across the terminals of the cathode of said second tube.

8. The method of operating a plurality 40 of vacuum tubes connected in tandem, each of a plurality of said tubes comprising a control electrode and a cathode, which method comprises controlling the potential difference between the control electrode and the cathode of one of said tubes in accordance with the potential of an electrode 45 of a succeeding tube.

9. A multi-stage vacuum tube system comprising several vacuum tubes, each having a cathode, a source of voltage, and connections to said source for heating said 50 cathodes whereby the potential of one of said cathodes as regards said source is intermediate the potential of two succeeding cathodes.

10. A vacuum tube system comprising a 55 plurality of vacuum tubes connected in tandem, each of said tubes having an input electrode and an output electrode, means for providing a direct current path between the input electrode of one of said tubes and the 60 output electrode of another of said tubes, and means for testing the operation of one of said tubes, said testing means comprising means for inserting a measuring instrument in circuit with the output electrode of one 65 of said tubes, and means for disconnecting

the input electrode of the tube under test from the output electrode of the preceding tube.

11. A vacuum tube system comprising a plurality of vacuum tubes connected in tandem, 70 each of said tubes having an input electrode and an output electrode, means for providing a direct current path between the input electrode of one of said tubes and the output electrode of another of said tubes, 75 and means for testing the operation of one of said tubes, said testing means comprising means for inserting a measuring instrument in circuit with the output electrode of one of said tubes, and means for disconnecting 80 the output electrode of the tube under test from the input electrode of the succeeding tube.

12. A vacuum tube system comprising a plurality of vacuum tubes connected in tandem, 85 each of said tubes having an input electrode and an output electrode, means for providing a direct current path between the input electrode of one tube and the output electrode of another of said tubes, and means 90 for testing the operation of one of said tubes, said testing means comprising means for inserting a measuring instrument in circuit with the output electrode of one of said tubes, means for disconnecting the input 95 electrode of the tube under test from the output electrode of the preceding tube, and means for disconnecting the output electrode of the tube under test from the input electrode of the succeeding tube. 100

13. A vacuum tube system comprising a plurality of vacuum tubes connected in tandem, each of said tubes having an input electrode and an output electrode, an input circuit and an output circuit, means for providing a direct current path between the input electrode of one of said tubes and the output electrode of another of said tubes, means for supplying current to said output circuits, and means for testing the operation 110 of one of said tubes, said testing means comprising means for preventing the output circuit current of the preceding tube from influencing the potential of the control electrode of the tube under test, and means for preventing the output circuit current of the tube under test from influencing the potential of the control electrode of the succeeding tube. 115

14. A vacuum tube system comprising a 120 plurality of vacuum tubes connected in tandem, each of said tubes having an input electrode and an output electrode, an input circuit and an output circuit, means for providing a direct current path between the input electrode of one of said tubes and the output electrode of another of said tubes, means for supplying current to said output circuits, and means for testing the operation 125 of one of said tubes, said testing means com- 130

prising means for applying to the input electrode of one of said tubes a constant potential independently of the output circuit of the preceding tube.

5. 15. The combination with a vacuum tube having a control electrode of a plurality of sources of potential for said electrode one of said sources being independent of the elec-

trical characteristics of said tube and another of said sources being dependent on said 10 electrical characteristics.

In witness whereof, we hereunto subscribe our names this 7th day of May A. D., 1919.

ROBERT C. MATHES.
HARRY S. READ.
